Primary Examiner — John Windmuller(74) *Attorney, Agent, or Firm* — Clause Eight IPS; Michael Catania**CLAIM**

The ornamental design for an antenna, as shown and described.

DESCRIPTION

FIG. 1 is a top plan view of an antenna with broken lines showing a cover.

FIG. 2 is a side plan view of the antenna of FIG. 1.

FIG. 3 is a top perspective view of the antenna of FIG. 1.

FIG. 4 is a bottom plan view of the antenna of FIG. 1.

FIG. 5 is a side view of the antenna of FIG. 1; and,
FIG. 6 is a bottom perspective view of the antenna of FIG. 1.
The broken line showing is for illustrative purposes only and
forms no part of the claimed design.**1 Claim, 2 Drawing Sheets**|
